PLAIN OR SATCHEL BAG-MAKING MACHINE

Gordon William French, Bristol, England, assignor to Beasley, French and Company Limited, Bristol, England

Application August 19, 1939, Serial No. 291,048
In Great Britain September 1, 1938

1 Claim. (Cl. 93—20)

This invention comprises improvements in and relating to plain and satchel bag-making machines of the type in which paper and like bags are made from a continuous web of paper or other suitable material folded and seamed into continuous tubular form and then fed to mechanism which severs the tubular material into suitable lengths in a manner to enable bottom folding mechanism to operate to seal one end of the tube to form the bags. The machines are of the high speed automatic type.

The primary object of the present invention is to enable a number of bags to be made side by side on a normal width machine thus economising in the cost of producing bags of small dimensions.

In present practice bag-making machines of the type described capable of making large bags will only operate when making small bags to provide a single line of bags from a single tube of material. The present invention therefore proposes a method and arrangement to enable small bags to be manufactured side by side on a machine the maximum capacity of which is sufficient for making bags of a size at least equal to the two or more small bags which may be made thereon according to the present invention.

Another object of this invention is to provide a paper-bag-making machine for plain, satchel type or block bottom bags with means arranged to fold and also seal the appropriate edges of sheet material into a number of tubes to be cut into bag lengths within the capacity normally available for a single wide class of bag, whereby sets of bags narrower than the said wide class of bag can be produced simultaneously instead of a single set of the wide class of bag.

In carrying the invention into practice a machine for making plain, satchel type, or block bottom bags is arranged to enable the paper or other suitable material to be folded and seamed into two or more tubes arranged side by side as an alternative to the normal arrangement which enables one such tube only to be worked on a given machine. In one embodiment taking for example two tubes arranged side by side, the material is folded so that the seams in the tube are at or near the inner or adjacent edges of the two tubes. By this means the two tubes may be kept close together and within the position normally occupied by a single tube of little more than double the size of one of the two tubes without any necessity for deflecting the paper or other material from its normal line. The two or more tubes of material may be made up from

two or more separate reels of paper or other suitable material or a single reel may be used and passed over or through suitable cutting or slitting mechanism to divide the web of paper or other suitable material longitudinally into the required number of strips which are then fed to the folding mechanism for folding them into the two or more tubes. The separate webs of material or the single web divided into a number of strips may, if desired, be of equal width or the widths of the two or more strips may vary. In this way two or more sets of bags of equal dimensions may be formed side by side on the machine or alternatively paper bags of different widths may be formed simultaneously on the same machine. The folding mechanism for folding the strips of material into tubular form is so arranged that the inner edges of the strips are folded over to form a relatively narrow strip whilst the other side is folded over to an extent equal to or almost equal to the full width of each paper bag. The folding operation is arranged so that the strips of material are folded over a suitable former plate. Two or more sets of pasting mechanism are provided in suitable positions to paste the seamed joints of the tubes. The tubes of folded material then pass along separate former plates in the usual manner to the cutting and folding mechanism which severs the upper and lower portions of each tube preferably in stepped formation so as to enable the folding mechanism to fold the cut-off sections of tubular material so as to produce an effective seal at the bottom of the bags.

The cutting mechanism for severing the sections of tube for formation into individual bags may be of the type in which a pair of rotary cutters make separate cuts in the upper and lower sides of the tubular sheet material, the two cuts being arranged in stepped relationship to each other so as to form the ends of the bags at one operation.

In order that this invention may be clearly understood and readily carried into effect, a sheet of drawings is appended hereto illustrating an embodiment thereof, and wherein—

Fig. 1 is a side elevation view of the slitting and tube forming means.

Fig. 2 is a plan view of the slitting device and tube forming plates.

Fig. 3 is a detail sectional front view of the preferred form of the slitting device.

Referring to the drawing it is preferred to employ a single roll of paper 1, the unwound paper 2 being passed over the usual feeding

rolls to a pasting stage 3 where a pair of axially spaced suitable paste wheels 4 (only one being visible) apply lines of paste to the web of paper at the required positions, e. g., along the outer edges thereof, the lines of paste being indicated by the shaded parts 5 in Fig. 2. The pasted web then passes around suitable rollers 6 to hold it taut and is then fed past a cutting or slitting stage 7 whereby the web of paper is divided longitudinally into a pair of strips 2a, 2b. The paper web is thus divided into a pair of strips of similar or dissimilar widths each having a pasted edge 5 ready to be passed to the folding stage 8 where each strip is folded into tubular form. Each folding mechanism is of any suitable well known type and is shown as comprising a parallel pair of former plates 9 and 10 and two pairs of rubber surfaced wheels 18, 19, 20 and 21, known as tubing wheels. The rubber treads of these wheels revolve freely simply by contacting the paper, the proportions of paper folded on either side of each plate being determined by the position of the plates 9 and 10 in relation to the web of paper, the wheels 18, 19, 20 and 21 ensuring that the paper is wrapped snugly round the plates, the folding being assisted by the axes of the rollers being inclined in relation to the longitudinal edges of the plates 9 and 10 as shown in Fig. 2, the folding being such that the seams 11 in the individual tubes are at or near the adjacent edges of the tubes. This minimises the space 12 between the former plates and enables the total width of the tubes to be kept within the maximum width of a single tube of paper which the machine is capable of handling and at the same time enabling two series of bags to be produced side by side thus utilising the maximum capacity of the machine even when making bags of relatively small dimensions. By adding to the number of slitting stages, former plates and pasting rollers more than two lines of tubes can be produced.

The cutting or slitting mechanism may as shown in Fig. 3 conveniently comprise one driven wheel or roller 13 of steel or other suitable material having one face slightly recessed or undercut as at 14 so as to form a relatively sharp edge at the periphery of the roller, and a cutting disc 15 having a bevelled edge 16 the face of

which is held or urged into resilient contact with the wheel or roller, e. g., by a coiled compression spring 17. Either the roller or disc or both may be rotated mechanically but preferably one is rotated positively and the other is driven by the frictional contact therewith. The roller and disc are preferably arranged so that their peripheries overlap each other slightly thus ensuring an effective cutting or slitting of the material.

When the lengths of tubular material are of uniform width the customary cutting rolls can be employed which normally with a single length of tubing cut the tubular material transversely at stepped parts to afford flaps for folding over and closing the base ends of the bag sections, the normal transverse blade in each cutting roll being removed from its appropriate securing device and a pair of shorter blades fitted in lieu thereof. The cutting rolls can be speeded up as desired by existing known means to shorten the length of each bag section as required. When bags of different width but uniform length are to be produced the same method may be adopted but when sets of bags of distinctive length are required, a special cutting device can be substituted for the normal and embody separately driven pairs of cutting rolls each driven at a predetermined speed. When the bag sections are of uniform length the normal mechanism for folding over the flaps can with very slight, if any, adaptation be employed, but when sets of bags of different length are to be produced separate folding and sealing means would have to be provided for at least one set of bag sections.

I claim:

In a machine for making plain, satchel type or block bottom bags, the combination with slitting means adapted to slit the sheet material into longitudinal side by side continuous strips of means to apply to the outer edges of the strips marginal coatings of an adhesive, means to fold relatively narrow inner marginal edges of the strips away from each other, and means to fold relatively wide parts of the strips towards the said relatively narrow marginal folded inner edges so as to obtain separate tube forming seams in close proximity to each other.

GORDON WILLIAM FRENCH.
